UNITED STATES PATENT OFFICE.

WALTER GREIG, OF NIAGARA FALLS, NEW YORK, ASSIGNOR TO AMERICAN SALES, BOOK COMPANY, LIMITED, OF TORONTO, ONTARIO, CANADA. A CORPORATION OF ONTARIO, CANADA.

MANIFOLDING SALES-BOOK.

1,165,590.

Specification of Letters Patent. Patented Dec. 28, 1916.

Application filed September 30, 1913. Serial No. 792,551.

To all whom it may concern:

Be it known that I, WALTER GREIG, a citizen of the United States residing at Niagara Falls, in the county of Niagara and State of New York, have invented certain new and useful Improvements in Manifolding Sales-Books, of which the following is a full, clear, and exact description, such as will enable others skilled in the art to which it appertains to make and use the same.

My present invention relates to manifolding sales books and has particular relation to means for detachably securing pads, particularly of so-called triplicate arrangement, to the covers of such books.

It has for its object to provide a simple and practical sales book holder having pad holding means which may be adjusted in the course of manufacture to take pads of different sizes.

In the accompanying drawing, wherein is shown one of various possible embodiments of my invention, Figure 1 is a perspective view of a portion of a holder sufficient to illustrate one embodiment of the present invention; and Fig. 2 is an end elevational view of a complete sales book in normal operative position.

Similar reference characters refer to similar parts throughout both views of the drawing.

Referring now in detail to the accompanying drawing, and more particularly to Fig. 2, it will be seen that the present invention comprises a holder having a main or bottom cover 1 to which is flexibly connected a top cover 2 by means of a hinge 3 extending along one of the side edges. The opposite side edge is provided with a second hinge 4 for attaching an auxiliary back or support 5 holding a pad for receiving inscriptions. This pad in the present case is secured thereto in any desired manner, and comprises a plurality of sets of original and duplicate leaves 6 and 7, respectively, and has associated therewith a double-faced carbon sheet 8, represented by the heavy line, adapted to be interposed therebetween. The pad comprising a plurality of sets of original and duplicate leaves is removably secured to the support 5 by means of a spring clamp 5' having teeth 5'' adapted to bear on the top of said pad. The triplicate record of the transaction is obtained upon

the leaves of another pad 10 secured at one side of the bottom cover 1. The leaves of the triplicate pad are preferably of tissue, and in use are interposed between the upper surface of the carbon sheet 8 and the under surface of the original leaf 6. It will thus be seen that when the inscription is recorded upon the original leaf 6 it will be reproduced upon the upper surface of the triplicate leaf 7 and the under surface of the tissue sheet 11, which being translucent permits the inscription to be read through it. After the transaction is recorded the auxiliary back 5 is swung about the hinge 4 which permits the tissue leaf to be withdrawn from its normal operative position as shown in Fig. 2 and dropped to a position between the bottom cover 1 and the auxiliary back 5, as shown at 12. In this manner a complete record of all of the transactions is conveniently filed away.

The present invention resides more particularly in the means for holding or securing the pad 10 to the holder, and is shown more clearly in Fig. 1. The holding means comprises two sheet metal clips 13 and 14, secured adjacent the lower and upper edge, respectively, of the bottom cover 1 in any desired manner, as by means of rivets 15. The clip 13 is composed of resilient sheet metal bent back upon itself at 16 and having its upper and lower parts turned up to form flanges having between them a groove in which may be disposed a part of the back of the pad. These up-turned portions 17 and 18 of the upper and lower parts of the clip respectively provide an abutment adapted to prevent lateral and endwise movement of the pad, for the pasteboard back 20 of the pad, which is scored along the dotted lines 21 at which the leaves of the pad are stitched, as well as along the dotted line 22 closely adjacent thereto, thereby permitting the cover to be bent to conform to the angle of the clip. The other clip 14 comprises two parts, the base portion 14 of which is secured to the cover of the book by rivets 15, as above described, and is provided at one side with a flange 23 similar to that of the lower clip. The upper portion 24 of the clip is also provided with a similar flange 25 corresponding to the portion 17 of the lower clip. These parts are spaced apart to form a groove in which is disposed

part of the pad back. The upper and lower portions of that clip, however, are hinged together at 26 and provided with a coiled spring 27 for yieldingly holding them in the position shown. A thumb notch 28 on the top portion 24 of the clip permits the operator to grasp it readily and swing it about the hinge 26 for inserting or removing a book or pad cover.

10 The method of operation of a sales book of this type is substantially as follows: When it is desired to insert a triplicate book 10 in the holder, the operator first raises the upper portion 24 of the clip 14 by means of the notch 28 and then inserts the attaching member or cover 20 of the triplicate book into the lower clip between its upper and lower portions. The scored lines 21 and 22 permit the cover to conform to the shape 15 of the clip more readily. On releasing the upper part 24 of the clip 14 the same will swing down under the action of the spring 27 and firmly clamp the cover portion of the book 10 in position. The upright portions 20 of both clips terminate substantially midway between the top and bottom of the original pad, as shown in Fig. 2, whereby the triplicate leaves will lie flat and completely cover the carbon sheet, thus permitting 25 the entire transaction to be properly recorded.

By having the holding means in two parts a large stock of these parts may be kept constantly on hand by the manufacturer of the 30 holders and placed upon the covers of the holders according to the requirements of the order, for some concerns prefer a longer or shorter sales book than others. The use of special machines and dies for stamping 35 out complete holders made from a single piece for the various sizes required is accordingly eliminated. It is also to be noted that there is great saving in the amount of material used, thus greatly reducing the 40 weight of the book as well as its cost of manufacture.

It is thus seen that the present invention is particularly designed for accomplishing,

among others, all of the objects and advantages above set forth.

50

Having described my invention, what I claim as new and desire to secure by Letters Patent is:

1. In a device of the character described, a cover, and a retaining device comprising 55 a base secured to the cover and having an up-turned flange, an upper part hinged to the base and provided with a similar flange disposed to form a groove between the flanges, and a spring pressing the two parts 60 together.

2. A support, a pad, and means for securing the pad to the support, comprising a sheet metal clip having a base attached to the support, an upper part hinged to the 65 base, and a spring pressing the parts together; the parts each provided with an up-turned flange having a space between them forming a groove in which part of the pad may be disposed.

70

3. In a device of the character described, a cover, and a retaining device comprising a base secured to the cover and having an up-turned flange, an upper part provided with a similar flange, the flanges forming a groove 75 between them; the upper part being hinged to the base, the hinge being at an angle to the flanges, and a spring pressing the base and upper part together.

4. A support, a pad, and means for securing the pad to the support, comprising a sheet-metal clip having a base attached to the support, an upper part hinged to the support, and a spring pressing the parts together; each of the parts being provided 80 with an upturned flange disposed substantially at right angles to the hinge, the flanges forming a groove in which part of the pad may be disposed to secure it to the support.

In testimony whereof I affix my signature, 85 in the presence of two witnesses.

WALTER GREIG.
